UNITED STATES PATENT OFFICE.

WILLIAM H. BUTLER AND WILLIAM R. LANDFEAR, OF BROOKLYN, NEW YORK; SAID LANDFEAR ASSIGNOR TO SAID BUTLER.

BOX-FILLING MACHINE.

SPECIFICATION forming part of Letters Patent No. 482,542, dated September 13, 1892.

Application filed September 25, 1891. Serial No. 406,844. (No model.)

To all whom it may concern.

Be it known that we, WILLIAM H. BUTLER and WILLIAM R. LANDFEAR, citizens of the United States, residing at Brooklyn, county 5 of Kings, State of New York, have invented certain new and useful Improvements in Box-Filling Machines, fully described and represented in the following specification and the accompanying drawings, forming a part of 10 the same.

This invention relates to box-filling machines, and especially to machines used in filling that class of boxes known as "slide-boxes," in which the box proper is inclosed within a 15 tubular cover or sheath.

The object of the present invention is to improve the general construction of this class of machines and the groups of mechanism employed therein, and especially to provide 20 a machine in which the entire operation shall be automatic, the box being formed from a blank or web, filled with the material or articles to be packed, inclosed within the tubular cover or sheath, which is automatically 25 brought into position for this purpose, and the covered box sealed by a sealing-strip of paper or similar material, which may be previously prepared, but is preferably formed from the web in the machine.

30 The machine embodying the invention has been constructed and is designed for packing cigarettes, and will be described as a cigarette-packing machine; but it will be understood that it is applicable, also, to packing other articles or material in boxes of similar form and that various parts of the mechanism may be used in box-filling machines of other classes or with mechanism of other form in machines of the same class.

40 For a full understanding of the invention a detailed description of a machine of the preferred form embodying the same will be given, reference being had to the accompanying drawings, forming a part of this specification, 45 in which—

Figure 1 is a front elevation of the machine in its preferred form. Fig. 2 is a side elevation showing the box-forming and cigarette-feeding mechanisms. Fig. 3 is a plan view. 50 Fig. 4 is a horizontal section taken above the carrier. Fig. 5 is a vertical section on the

line 5 of Fig. 3, showing the box-forming mechanism. Fig. 6 is a horizontal section on the line 6 of Fig. 5. Fig. 7 is a side elevation of the cigarette magazine and feeding devices. Fig. 8 is a central longitudinal section of the same. Fig. 9 is a detailed section of the cigarette-packing mechanism on an enlarged scale, taken on the line 9 of Fig. 8. Fig. 10 is a detail of the cam for operating the 60 cigarette-packing plunger. Fig. 11 is a section on the line 11 of Fig. 7. Fig. 12 is a section of the cover-feeding and box-covering mechanism, looking to the left on the line 12 of Fig. 4. Fig. 13 is a section of the same 65 on the line 13 of Fig. 4. Fig. 14 is a section looking to the right on the line 12 of Fig. 4. Fig. 15 is a section on the line 15 of Figs. 4 and 14. Fig. 16 is a similar section showing the parts in a different position. Fig. 17 is a 70 side elevation of the sealing mechanism on an enlarged scale. Fig. 18 is a section of the same on the line 18 of Fig. 3. Fig. 19 is a section on the line 19 of Fig. 18. Fig. 20 is a detail hereinafter referred to. Figs. 21 to 26 75 show a modification in which the boxes are formed from blanks fed from a magazine and the sealing mechanism is omitted. Fig. 21 is a front elevation similar to Fig. 1. Fig. 22 is a plan view. Fig. 23 is a horizontal section 80 of the box-blank magazine, showing the devices for delivering the bottom blank to the carrier. Figs. 24, 25, and 26 are sections on, respectively, the lines 24, 25, and 26 of Fig. 23. Figs. 27 to 34 are diagrams, partly in section, 85 showing the different steps in forming the product.

The frame of the machine may be of any construction suitable to support the operating parts. As shown, it consists of a standard A, carrying a base-plate B, provided with brackets or arms C D, upon which, respectively, the box-forming and box covering and sealing mechanisms are supported.

Upon the base-plate B is mounted the carrier E on a shaft F, supported inside the hollow standard, by which the boxes are carried to the different co-operating mechanisms, this carrier being rotated by an arm 10, provided with a bowl, which engages grooves or slots 11 on the under side of the carrier, so as to move the latter forward one step at each ro-

tation of the arm 10, the latter being carried by a vertical shaft G, which is operated from the main driving-shaft of the machine H through beveled gears 12. The main shaft H 5 may be driven by any suitable power connections, being shown as actuated by a pulley I, which may be thrown in or out of engagement with the shaft by a shifting-lever K, the shaft extending horizontally above the carrier and being mounted in vertical brackets L on the base-plate. The shaft G carries, also, an arm 13, which may be, as shown, a continuation of the arm 10 on the opposite side of the shaft, this arm 13 being connected by 15 a link 14 to a crank-arm 15 on shaft 16, which carries an arm 17, by which the plunger for removing the filled box from the carrier and inclosing it in the cover is actuated. The shaft 16 carries, also, an arm 18, provided 20 with a bowl 19, which runs in a groove 20 in a lever 21, pivoted at 22 and connected by a link 23 with the plunger, by which the covers are removed from the cover-magazine. The arm 13 carries a bowl 24, which runs in a groove 25 25 in one arm of a lever 26, pivoted at 27, the other arm of which actuates the plunger for advancing the covers into position to receive the filled boxes.

The carrier E is provided on its upper side 30 with a series of holders M, in which the boxes are held during the operation of filling and from which they are removed by a plunger in covering. These holders M form, also, matrices, with which a die co-operates to form the 35 blank into a box. The holders are equal in number to the feeding-grooves 11 on the under side of the carrier, so that the amount of feed is equal to the distance between two holders, and at each step forward different holders 40 are brought into proper position for co-operation with the other parts of the machine. A strong spring-catch S engages the grooves 11 successively and insures the accurate positioning of the holders after each feeding movement. As shown, the carrier is provided with 45 six holders; but it is evident that this number may be varied, as desired, and all the operations of the machine shown may be performed successively with a carrier provided 50 with but three holders, which successively assume the proper positions for receiving a box, filling the box, and removing the box from the carrier for covering. About this rotating carrier we group in proper position for co-operation therewith the various mechanisms 55 which form the complete machine, these mechanisms being the box-forming mechanism or mechanism for forming and delivering to one of the holders M a box to be filled, box-filling 60 mechanism by which the cigarettes are delivered to the box, a cover-magazine, and mechanism for delivering the tubular cover or sheath in position to receive the boxes, and covering mechanism by which the box is removed from the carrier and inclosed within 65 the cover. With these mechanisms there is preferably combined a sealing mechanism by

which a sealing-strip is applied to the covered box, so as to secure the box within the cover.

The box-forming mechanism will first be described. The boxes may be formed from blanks held in a magazine, in which case the box-forming mechanism will consist simply of means for delivering a blank from the 70 magazine to the holder on the carrier and a die for forming the box in the holder. In the preferred construction, however, which will now be described, the boxes are formed in the machine from a web of card-board or thick 80 paper, as usual in box-making machines.

Referring now especially to the main views and Figs. 5, 6, and 27 to 29, two co-operating cutting-rolls 28 are mounted at the rear of the machine on the frame C, by which the web X 85 of box-paper is advanced and cut to form a series of box-blanks connected at their ends, as shown in Figs. 5 and 6. These cutting-rolls 28 are driven from the main driving-shaft H by a chain 290 and sprocket-wheels, 90 the rolls being geared together to secure their proper action. Above the rolls 28 and geared therewith is a short shaft 29, carrying a crank-arm 30, which is connected by a link 31 to a bar 32, reciprocating between guides 33 and 95 provided with feeding-fingers 34. These feeding-fingers 34 engage the strip of box-blanks X, as shown in Fig. 6, and advance them over a supporting-roll in table 35, the throw of the feeding-fingers 34 being equal to the length of 100 a blank. The guide 33 above the bar 32 is constructed of spring metal, so as to yield and allow the fingers to be raised and pass over the sides of the blank as the fingers are withdrawn and insure their contact with the rear 105 edges of the blank for advancing the latter. The blanks X are successively advanced by the fingers 34 to a position above the holder M on the carrier, which has then been brought into position opposite the mechanism just described. The blank may be of sufficient length only to form the bottom and sides of the box, but, as shown, is extended on each end so as to form, also, a cover for the box, so that the latter is closed on all sides before being 110 inserted into the tubular cover or sheath. As the blank reaches the proper position above the holder and the feeding-fingers are withdrawn to feed forward another blank the blank is depressed into the holder and the 115 open box formed by the descent of the die 36, which is carried by a bar moving between guides 37 and actuated by a pitman 38 from an eccentric 39 on the main driving-shaft H. The die 36 carries a knife 40, by which the 120 blank is severed from the blank-strip as the box is formed.

Fig. 27 shows the box-blank in position for the descent of the die, Fig. 28 the blank severed and the box formed by the die, and Fig. 130 29 the position of the box in the holder when the die is withdrawn.

As will be seen by reference to Fig. 3, the filling mechanism by which the cigarettes are

delivered to and packed in the box thus formed is located, relatively to the carrier, one step in advance of the box-forming mechanism, just described, and, the box having been formed, the carrier is advanced by the arm 10 one step to the filling mechanism, which will now be described.

Referring especially to the main views and Figs. 7 to 11 and 30, the cigarette-magazine consists of a hopper N, mounted above the carrier and box-feeding mechanism, and from which the cigarettes are fed by a belt 42, forming the bottom of the hopper, and on which the cigarettes rest, this belt being carried by pulleys 43, the pulleys 43 being driven by a chain 44 and sprocket-wheels from the main driving-shaft H. To secure the proper feed of the cigarettes from the magazine and prevent clogging, a vibrating separator 45 is used, carried by a shaft 46, mounted in the sides of the magazine and provided outside the magazine with a slotted arm 47, which is engaged by a lever 48, actuated in one direction by a ratchet-wheel 49, carried by the shaft of pulley 43 and returned to position by the spring 50, a quick vibrating action being thus secured, which effectually prevents clogging of the outlet from the magazine. A buffer 51 is also provided for the separator. The tension of the belt 42 is preferably made adjustable, as shown, by mounting the bearing of pulley 43 to slide upon the base of the magazine, so that it may be adjusted by the screw 52, and scrapers 53 are provided for keeping the belt clean, thus securing its proper movement. From the belt 42 the cigarettes pass down an inclined raceway 54 to the packing mechanism, by which they are counted and packed in the box. The machine is adapted to pack ten cigarettes in a box, and the cigarettes are received from the raceway in a receiving-chamber upon narrow plates 55, which support the cigarettes at their ends and forming a swinging bottom for the receiving-chamber, these plates being pivoted by studs 1 and held normally in position to support the cigarettes by coiled springs 2, which yield to allow the plates to be forced by the packer to the position shown in dotted lines in Fig. 9, and the cigarettes to be thus delivered to the box in the holder M. The plates 55 are of sufficient length to hold five cigarettes and form a continuation of the raceway, there being just space between the end of the raceway and the outer fixed frame, in which the plates 55 are mounted, to receive the five cigarettes supported by the plates. Above the plates 55 is mounted a vertical reciprocating plunger 56, carried by a rod 57, sliding in guide 58, this plunger being actuated by a lever 59, having a pin-and-slot connection with the head of the plunger and provided with a bowl 60, running in a cam-groove 61 in a cam 62, carried by the main driving-shaft H. The cam is formed with two cam-surfaces at opposite sides of the wheel, so as to actuate the plunger twice during the rotation of the shaft

H, two layers of cigarettes being packed in each box, and, as will be seen from Fig. 10, the cams are constructed of different depths, so that the second throw of the plunger is less than the first by the thickness of a cigarette, the second layer of cigarettes thus being packed with just the pressure required. To secure the proper packing, the plunger 56 is also preferably made adjustable upon its shaft 57, as shown. It is desirable that the plunger 56 should make a quick return after delivering the cigarettes, and for this purpose a spring is provided by which the plunger is normally pressed upward, and the cam-groove 61 is so formed that the bowl 60 is released just as the plunger has reached its lowest point to permit the quick return of the plunger by the spring. The form of the filled box and its position in the holder are shown clearly in Figs. 8 and 30. From the filling mechanism the filled box is advanced by the carrier to the covering mechanism, which includes a magazine and means for delivering a tubular cover or sheath into position to receive the box and means whereby the latter is inserted endwise within it. As shown, the box-covering mechanism is three feeding steps in advance of the filling mechanism; but it will be understood that this will depend upon the number of holders with which the carrier is provided. By the use of a large number of holders a large capacity is attained with a low speed of the carrier, and the time between filling and covering permits the examination of the filled boxes. The covering mechanism may be varied widely and the covers may be placed in the magazine and fed therefrom in tubular form; but to permit a large number of covers to be packed in the magazine the covers are preferably packed flat in the magazine and mechanism is provided by which they are opened as they are brought into position to receive the boxes. This cover delivering and opening mechanism will now be described. The covers Y are packed flat in a vertical magazine O, mounted at one side of the path of the box as it is delivered from the carrier, and the bottom cover is fed from the magazine by a plunger 63, which is carried by a slide 64, connected to the link 23, through which it is actuated from lever 21, previously described. The plunger 63 has a set-screw and slot connection 3 with the slide 64, so that its throw may be adjusted to deliver the cover accurately. By reciprocating plunger 63 the cover is delivered in flat form in front of a second plunger 65, which is carried by a slide 66, having a pin-and-slot connection with the lever 26, previously described, this plunger 65 also having a set-screw and slot adjustable connection 3 with its slide 66, as in the case of the plunger 63. These two plungers 63 and 65 move at right angles to each other, the plunger 65 taking the flat box from plunger 63 and advancing it into the path of the filled box as the latter is moved from the carrier to the sealing mechanism. The plunger 65 also opens the cover by the following

means: The outer side wall 67 of the raceway on which the filled box is advanced is provided opposite the plunger 65 with a swinging spring-pressed finger *b*, which is curved so as 5 to guide the edge of the cover upward as it is pressed against it by the plunger and tend to open the cover, and the side wall 67 is provided, also, with an overhanging flange 5, beneath which the top of the cover rests when 10 fully opened. The inner side wall 68 of the raceway is inclined upwardly toward the raceway, and also has an overhanging flange 6, beneath which the top of the cover rests when fully opened. The operation of the construction 15 is shown clearly in Figs. 15 and 16, the cover being gradually opened by the pressure of the plunger, the spring-curved finger *b* yielding as the cover is advanced by the plunger, the incline on the under side of the wall 68 permitting the cover to open, and the cover being held in position when opened by the side walls 67 68 and their flanges 5 6. A central guide 69, carried on the outside wall 67 above the cover, aids, also, in holding the 20 cover in position; but this will not generally be found necessary.

For removing the filled box from the carrier and pushing it endwise into the cover opened to receive it, as just described, the 25 following means are provided: The plunger 70, by which the box is removed from the carrier, is carried by a slide 71, moving on a support 72 and connected by a link 73 to the arm 17, previously described. As previously stated, the box is preferably formed 30 with ends of sufficient length so that one is closed down to cover the filled box and the edge of the other end lapped down upon it, and it is necessary that these projecting ends 35 should be closed down prior to or during the operation of inserting the filled box into the cover. For the purpose of turning down the rear overlapping end the plunger 70 is constructed, as shown, with fingers *a*, arranged 40 to engage the overlapping rear end above the box. The other end may be lapped down upon this by engagement with the top of the cover as the box is inserted within it; but with inferior blanks it is desirable 45 to use for this purpose and for the purpose of holding the cover the center guide 69, previously described, which is beveled or rounded at its inner end, as shown in Figs. 14, 31, and 32, so that the end of the box is lapped down thereby and the filled box fully 50 closed before the box reaches the cover, as shown in Fig. 32, this construction aiding to secure the proper insertion of the box and cover. The guides 74, by which the filled box 55 is held in proper position to enter the cover, are made slightly narrower on the sides and top and bottom than the cover, so that the box is properly guided and will readily slip into the cover.

60 The action of the plunger in removing the box from the carrier and inserting it in the cover is shown clearly in Figs. 31 and 32.

The filled and covered boxes may be delivered by plunger 70 as the completed product of the machine, as shown in Fig. 33; but 70 a sealing mechanism is preferably used, as above stated, which mechanism will now be described.

Referring especially to Figs. 3 and 17 to 20, a strip of paper *Z*, perforated at points 75 distant from each other the length of the sealing-strip to be applied, is advanced by a feeding mechanism consisting of a roll 75, driven by beveled gears 76 from a shaft 77, operated from shaft *G*, and a spring-pressed roll 78, 80 coacting with the feeding-roll 75. The shaft of feeding-roll 75 carries a crank-disk 79, connected by a rod 80 with a crank-disk 81, carrying a spring-pressed pawl 82, which engages a ratchet 83, carried on the shaft of a paste-roll 84, mounted to rotate in a paste-fountain 85. The strip of sealing material *Z* is supported between the feeding-rolls 75 and paste-roll 84 by a guide 4, and the paste-roll is provided with a brake-disk 6, by which the paste-roll is stopped when not positively actuated. The paste-roll 84 is grooved to apply paste in two lines at the edges of the strips, and a spring 5, lying in the groove, supports the paper on the advance side of the paste-roll and 90 prevents its being carried around the roll by adhesion. From the paste-roll 84 the strip is advanced by a feeding-finger 7, engaging the perforations in the strip. This finger 7 is carried by an arm 86 on slide 66, previously described, and the feeding-finger 7 is pivotally mounted on the arm and spring-pressed, as shown, so as to be withdrawn from the perforations as it is moved backward and forced therein to engage and feed forward 95 the strip as it is advanced. To prevent the strip being carried backward by the drag of the finger, a spring-holding finger 87 is provided, engaging the perforations, the rear end of this finger forming a guide 8, by which 100 the strip is turned at right angles, so as to be fed forward to the boxes lying in a vertical plane. The feeding-finger 7, holding finger 87 and guide 8, engages the strip between the lines of paste, so that the free movement 105 of the fingers and strip is secured. The pasting-roll 84 is preferably constructed and operated to rotate during less than the full feed of the strip by the fingers, so that during a small part of the feed the strip is dragged 110 over the surface of the paste-roll, a tension upon the strip being thus secured, which insures its proper form. The leading end of the strip *Z* is carried by the feeding-finger 7 into the path of the filled and covered boxes 115 as they are advanced in line by the plunger 70, and the feed is sufficient to provide a sealing-strip of such a length as to cover the end of the box and lap over upon each side. As 120 paste is applied the full length of the strip 130 on the side next the box, it will be seen that the sealing-strip is pasted on the end of the box and two sides, thus securing the box in the cover. A guide *T* is provided, having a

groove in which the strip Z is held in correct position while being fed forward, thus insuring the proper attachment of the sealing-strip to the boxes.

5 For the purpose of severing the strip at the desired points and pressing the strip upon the box so as to secure it the following means are provided: A knife 88 is carried by a rock-shaft 9, mounted in arms on the under side 10 of the frame D, and is operated by a crank-arm thereon, having a pin connection with a slotted link 89, carried by an arm 90, secured to and moved by the slide 64, so that as the slide is actuated to carry the plunger into position to take a cover from the magazine the knife is actuated to sever the strip, and as the plunger reaches its inner position in delivering the covered box the knife is withdrawn. The boxes having the severed sealing-strip attached to their forward ends are advanced by the plunger 70 between two feeding-rolls 91, mounted on vertical studs 92, mounted in frame D, these feeding-rolls being preferably faced with rubber or similar material to secure the proper feed. One of the rolls 91 is rotated intermittently by a disk 93 on its shaft, carrying a spring-pressed pawl 94, which is engaged by a friction-disk 95, mounted on the shaft and oscillated by the 25 slide 64, to which it is connected by a link 96. The feeding-rolls 91 are thus actuated at proper times to deliver a box as it is received from the line advanced by the plunger 70, and the speed of the rolls 91 is such as to re-30 move the leading box from the path of the strip Z before the latter is advanced by the feeding mechanism.

The completed, covered, and sealed box is shown in Fig. 34.

40 The operation of the various mechanisms has already been fully described, and the general operation of the mechanism will be understood from a brief description of the combined operation of the different mechanisms. 45 The box-forming mechanism is constructed to form a box-blank from the web and feed forward a blank into position above the carrier at each step forward of the latter, and as each holder on the carrier is thus brought 50 into position with a blank above it the box-forming die or plunger severs the blank and forms the open box within the former. At the same time the box in the holder next in advance is being filled with cigarettes by the 55 filling mechanism and a filled box in the holder three steps in advance of the filling mechanism is being removed from the carrier by the plunger 70 and forced into the cover which has been delivered from the cover-magazine to the raceway in front of the filled box by the plungers 63 65 and opened to receive the latter. A gummed sealing-strip Z has meanwhile been fed forward by the strip-feeding mechanism and is now in the path of the 60 filled boxes. As the filled box is inserted in the cover the line of covered boxes is advanced the length of one box by the plunger,

and the leading box of the line is thus carried against the strip and then between the feeding-rolls 91, with the sealing-strip pasted 70 to the end, the strip being severed by the knife 88 as the box and strip move forward. The filling-box, with the strip attached, is then advanced by feeding-rolls 91 at such a speed as to remove the box from the path of the 75 sealing-strip before the latter is again advanced by the feeding mechanism. The various steps of box covering, filling, and delivering having been completed and the parts co-operating with the carrier returned to position for another operation, the carrier is advanced another step and the operation just described is repeated.

While the box-forming mechanism will preferably be constructed so as to form the box 85 from the web, the boxes may be formed from previously-prepared blanks, as above stated. In Figs. 21 to 26 we have shown such a modification. The general construction of the machine is identical with that previously described, except that the sealing mechanism is omitted and a box-magazine P, holding the box-blanks, is mounted above the carrier in position to deliver a box-blank to a holder M one step in advance of the die or plunger 36, 95 by which the box is formed in the holder, as previously described.

For the purpose of securing the taking of a single blank from the magazine by the holder M the following construction (shown in detail 100 in Figs. 23 to 26) is preferably used. The magazine P is open at the bottom and the box-blanks X are supported therein by fingers 97 98, mounted on and held slightly below the bottom of the magazine. These fingers are 105 connected at but one end to the magazine and are free at the end in advance relatively to the movement of the carrier, so that the box-blanks are free to be carried out from the fingers and beneath the magazine-walls. The finger 97 extends entirely across the bottom of the carrier, so as to provide a sufficient support for the blanks, while the finger 98 need extend only to the edge of the holder, as shown in Figs. 23 and 26, to insure the proper 110 position of the edge of the blanks. The carrier is provided above each of the holders M with lips 99, forming a recess of the same width as the box-blanks and of sufficient depth to receive a single blank, these recesses being 115 so formed that they are directly below the line of box-blanks in the magazine as the holder is in position beneath the latter, and the fingers 97 98 being set in grooves in the carrier, so as to allow the blanks to rest therein 120 with the bottom blank inside the recess. As the carrier advances from the position shown in Figs. 23 to 26, therefore, the bottom blank is carried forward therewith, held in the recess formed by the lips 99, and as the next 125 holder is brought into position the bottom blank is received in the recess above it. The construction of the die 36 and its operation upon the box-blank thus received are the same

as in the construction previously described, in which the blanks are formed from the web, except that the knife 40 is omitted, and the combined operation of the various mechanisms is the same as that previously described and need not be repeated.

It is evident that many modifications may be made in the machine shown as embodying the invention, and it is not to be limited to the specific form of any of the mechanisms or devices shown, as other constructions of the same general character may be substituted therefor without departing from the invention.

15. What we claim is—

1. The combination, with a box-holder, of mechanism co-operating with said holder to form and deliver boxes thereto, a box-filling mechanism by which the boxes are filled, and 20 a covering and delivering mechanism by which the filled boxes are delivered from the holder and inserted in tubular covers, substantially as described.

2. The combination, with a box-holder, of 25 mechanism co-operating with said holder to form and deliver boxes thereto, a box-filling mechanism by which the boxes are filled, a covering and delivering mechanism by which the filled boxes are delivered from the holder 30 and inserted in tubular covers, and a sealing mechanism for applying sealing-strips to said boxes, substantially as described.

3. The combination, with an intermittently-moving carrier provided with a plurality of 35 box-holders, of mechanism co-operating with said holder to form and deliver boxes thereto, a box-filling mechanism to which the boxes are advanced from the box-forming mechanism by the carrier and by which they are 40 filled, and covering and delivering mechanism to which the boxes are advanced from the filling mechanism and by which they are delivered from the carrier and inserted in tubular covers, substantially as described.

45. 4. The combination, with an intermittently-moving carrier provided with a plurality of box-holders, of mechanism co-operating with said holders to form and deliver boxes thereto, a box-filling mechanism to which the boxes 50 are advanced from the box-forming mechanism by the carrier and by which they are filled, covering and delivering mechanism to which the boxes are advanced from the filling mechanism and by which they are delivered 55 from the carrier and inserted in tubular covers, and sealing mechanism by which sealing-strips are applied to the boxes, substantially as described.

5. The combination, with an intermittently-moving carrier provided with a plurality of 60 box-holders, of feeding mechanism for advancing a strip of box-blanks to said carrier, mechanism co-operating with said holders to form boxes from said blanks and deliver 65 them to the holders, a box-filling mechanism to which the boxes are advanced from the box-forming mechanism by the carrier and

by which they are filled, and covering and delivering mechanism to which the boxes are advanced from the filling mechanism and by 70 which they are delivered from the carrier and inserted in tubular covers, substantially as described.

6. The combination, with an intermittently-moving carrier provided with a plurality of 75 box-holders, of cutting and feeding mechanism for forming a strip of box-blanks, a cutter and box-forming die for severing blanks from said strip and forming boxes in said holders, a box-filling mechanism to which the 80 boxes are advanced from the box-forming mechanism by the carrier and by which they are filled, and covering and delivering mechanism to which the boxes are advanced from the filling mechanism and by which they are 85 delivered from the carrier and inserted in tubular covers, substantially as described.

7. The combination, with an intermittently-moving carrier provided with a plurality of box-holders, of mechanism co-operating with 90 said box-holders to form and deliver boxes thereto, a magazine containing the articles to be packed, to which the boxes are advanced from the box-forming mechanism, feeding and packing mechanism for feeding the articles 95 from the magazine and packing them in the boxes, and a covering and delivering mechanism to which the boxes are advanced from the packing mechanism and by which they are delivered from the carrier and inserted in 100 tubular covers, substantially as described.

8. The combination, with an intermittently-moving carrier provided with a plurality of box-holders, of means coacting with said 105 holders to supply them with boxes, a magazine containing the articles to be packed, to which the boxes are advanced by the carrier, feeding mechanism for feeding the articles from the magazine, a counting and packing mechanism by which the articles are counted 110 and packed in the boxes, and a covering and delivering mechanism to which the boxes are advanced from the packing mechanism and by which they are delivered from the carrier and inserted in tubular covers, substantially 115 as described.

9. The combination, with an intermittently-moving carrier provided with a plurality of 120 holders, of means coacting with said holders to supply them with boxes, a magazine containing the articles to be packed, feeding mechanism for feeding the articles from the magazine, a receiving-chamber having a 125 swinging bottom, to which the articles are delivered from the magazine, a reciprocating plunger by which the articles are removed from the chamber and packed in the boxes, and a covering and delivering mechanism to which the boxes are advanced from the packing mechanism and by which they are 130 delivered from the carrier and inserted in tubular covers, substantially as described.

10. The combination, with an intermittently-moving carrier provided with a plurality

- of box-holders, of mechanism co-operating with said box-holders to form and deliver boxes thereto, a filling mechanism to which the boxes are advanced from the box-forming mechanism by the carrier and by which they are filled, a plunger for delivering the filled boxes from the carrier, and a cover-magazine and feeding mechanism for delivering tubular covers in the path of the filled boxes as they are delivered by the plunger, substantially as described.
11. The combination, with a holder adapted to receive and hold a box, of box-filling mechanism by which the box is filled, a plunger for delivering the filled box from the holder, a cover-magazine in which the tubular covers are packed flat, and feeding and opening mechanism by which a cover is delivered open in the path of the filled box as it is advanced by the plunger, substantially as described.
12. The combination, with a holder adapted to receive and hold a box, of box-filling mechanism by which the box is filled, a plunger for delivering the filled box from the holder, a vertical cover-magazine in which the covers are packed flat, a plunger by which the bottom cover is removed endwise from the cover-magazine, and a plunger and co-operating devices advancing the cover sidewise into the path of the filled box and opening the cover, substantially as described.
13. The combination, with a holder adapted to receive and hold a box, of box-filling mechanism by which the box is filled, covering and delivering mechanism by which the filled box is delivered from the holder and inserted in a tubular cover, and sealing mechanism by which a sealing-strip is applied to said box, substantially as described.
14. The combination, with a holder adapted to receive and hold a box, of box-filling mechanism by which the box is filled, covering and delivering mechanism by which the filled box is delivered from the holder and inserted in a tubular cover, feeding mechanism by which a pasted web is advanced into the path of the filled box, a cutter for severing a sealing-strip from said web, and means for pressing said strip on said box, substantially as described.
15. The combination, with a holder adapted to receive and hold a box, of box-filling mechanism by which the box is filled, covering and delivering mechanism by which the filled box is delivered from the holder and inserted in a tubular cover, feeding mechanism by which a pasted web is advanced into the path of the filled box, a cutter for severing a sealing-strip from said web, and feeding and pressing rolls to which the boxes are advanced by the delivering mechanism, substantially as described.
16. The combination, with magazine N and feeding-belt 42, of vibrating separator 45 above said belt, substantially as described.
17. The combination, with magazine N, feed-
- ing-belt 42, and raceway 54, of spring-supported plates 55 and reciprocating packing-plunger 56, substantially as described.
18. The combination, with spring-supported plates 55, of reciprocating packing-plunger 56 and means for actuating said plunger with a shorter throw at certain strokes, substantially as described.
19. The combination, with a reciprocating packing-plunger and a holder for the material or articles to be packed, of means for actuating said plunger with a shorter throw as successive layers of the material or articles are packed, substantially as described.
20. The combination, with holder M, of a box-delivering plunger 70, having fingers *a* for turning down one end of the box and guide 69 above the path of the box for turning down the opposite end, substantially as described.
21. The combination, with a plunger for advancing a flat tubular cover sidewise, of devices co-operating therewith to open the cover, substantially as described.
22. The combination, with a plunger for advancing a flat tubular cover sidewise, of devices co-operating therewith to open the cover and means for inserting a box in said cover, substantially as described.
23. The combination, with a plunger for advancing a box, of a plunger for advancing a flat tubular cover sidewise into the path of the box and devices co-operating with said plunger to open the cover, substantially as described.
24. The combination, with the cover-magazine O, of plunger 63 for removing the bottom cover endwise from the box, plunger 65, advancing the box sidewise, and devices co-operating with said plunger to open the box-cover, substantially as described.
25. The combination, with plunger 65, of bar 67, having spring inclined finger *b*, and bar 68, having a guiding-incline on its lower side, substantially as described.
26. The combination, with plunger 65, of bar 67, having spring inclined finger *b* and overhanging flange 5, and bar 68, having a guiding-incline on its lower side and overhanging flange 6, substantially as described.
27. The combination, with plunger 65, of bar 67, having the inclined spring-pressed finger *b*, substantially as described.
28. The combination, with box filling and covering mechanism, of sealing mechanism for applying a pasted sealing-strip on the end and overlapping the sides of the box, substantially as described.
29. The combination, with box filling and covering mechanism, of feeding mechanism for advancing a pasted strip into the path of the filled and covered box and pressing devices for pressing the strip on the box, substantially as described.

30. The combination, with box filling and covering mechanism, of feeding mechanism for advancing a pasted strip into the path of the filled and covered box and feeding and 5 pressing rolls 91, substantially as described.

31. The combination, with box-filling mechanism, of covering and delivering mechanism adapted to cover the boxes and deliver a line of boxes, feeding mechanism for advancing a 10 pasted strip into the path of the filled and covered boxes, and feeding and pressing rolls

91, run at a higher speed than the delivering mechanism, substantially as described.

In testimony whereof we have hereunto set our hands in the presence of two subscribing 15 witnesses.

WM. H. BUTLER.

WILLIAM R. LANDFEAR.
